UNITED STATES PATENT OFFICE.

LEO POTTER, OF NEW YORK, N. Y., ASSIGNOR TO EMIL POTTER, OF NEW YORK, N. Y.

DESIGN FOR AN IMAGE.

48,650.

Specification for Design.

Patented Feb. 29, 1916.

Application filed January 15, 1915. Serial No. 2,486. Term of patent 3½ years.

To all whom it may concern:

Be it known that I, LEO POTTER, a citizen of the United States of America, residing in the borough of Manhattan, city, county, and State of New York, have invented a new, original, and ornamental Design for an Image, of which the following is a specification, reference being had to the accompanying drawing, forming part thereof, which shows an image embodying my new design.

I claim:

The ornamental design for an image, as shown.

LEO POTTER.

Witnesses:

MAURICE FREEMAN,
CHARLES A. MATHE.
